Term of patent 14 years

(Cl. D3—16)

FIG. 1.

FIG. 2.

FIG. 3.

FIG. 1 is a front elevation of a slip-type undergarment showing my new design;

FIG. 2 is a view similar to FIG. 1 showing one side of the garment opened at its front split; and

FIG. 3 is a view showing the garment in rear elevation.

The front split and bottom border configurations are intended to be illustrative of lace.

The dominant feature of this design resides in the provision of opposed lace trim edges at the front of the garment extending above the bifurcation of the legs at the crotch region, together with lace trim extending along the bottom edge of the slip-type undergarment.

I claim:

The ornamental design for a slip-type undergarment, substantially as shown and described.
